UNITED STATES PATENT OFFICE

2,650,570

PENHOLDER

Billy N. Voelecker, Shreveport, La.

Application December 3, 1951, Serial No. 259,603

1 Claim. (Cl. 120—108)

1

The present invention relates to new and useful improvements in fountain pen holders or stands of the desk type and has for its primary object to provide, in the manner as hereinafter set forth, a device of this character comprising novel means for positively preventing the grip portion of the pen from being coated with ink when said pen is inserted, and subsequently smearing the thumb and fingers of the user when said pen is removed from the holder.

Another very important object of the invention is to provide a device of the aforementioned character comprising unique means for receiving and guiding the writing end of the pen without touching and smearing the entrance or mouth portion of the holder with ink to be picked up by the grip portion and later transferred to the fingers of the user.

Other objects of the invention are to provide a fountain pen holder of the character described which will be comparatively simple in construction, strong, durable, highly efficient and reliable in use, compact, attractive in appearance, and which may be manufactured at low cost.

All of the foregoing and still further objects and advantages of the invention will become apparent from a study of the specification, taken in conjunction with the accompanying drawing, wherein like characters of reference designate corresponding parts throughout the several views, and wherein:

Figure 1 is a vertical sectional view, showing a holder constructed in accordance with the present invention in use.

Figure 2 is a view in vertical section through the device with the pen omitted.

Figure 3 is a fragmentary view in vertical section, taken substantially on the line 3—3 of Figure 1.

Figure 4 is a detail view in perspective of the reciprocating pen point cup.

Figure 5 is a vertical sectional view through a modified form of the device.

Referring now to the drawing in detail, it will be seen that reference character 6 designates a body of suitable shape, size and material comprising a flat lower face 7. Secured by screws 8 on the flat bottom 7 of the body 6 is a metallic base plate 9 having adhesively secured therebeneath a pad 10 of felt or any other suitable material.

Extending at an inclination through the body 6 is a bore or socket 11 comprising a reduced upper end portion or mouth 12. The socket 11 is for the reception of the writing end portion of a fountain pen 13.

2

The cylindrical socket 11 has formed longitudinally therein diametrically opposite grooves or ways 14 which extend from the lower end of said socket to the shoulder 15 provided by the reduced upper portion 12. A base member 16 is mounted on the plate 9 in the lower portion of the socket 11.

The end portions of a bar 17 are slidably engaged in the grooves 14. Fixed on the bar 17 is a cup 18 of plastic, metal, or any other suitable material for the reception of the point 19 and the nib 20 of the fountain pen 13. The cup 18 is further provided with an opening 21 which accommodates the pen point 19. A light coil spring 22 is mounted on the base 16 and engaged beneath the bar 17 for yieldingly urging the cup 18 upwardly in the socket 11.

Suitable means may, if desired, be provided for releasably securing the pen 13 in the holder against the action of the light coil spring 22. In the embodiment shown, a plurality of spring fingers 23 are mounted in the reduced mouth portion 12 of the socket 11 for engagement with an annular bead 24 which is fixed on the pen 13.

It is thought that the operation of the device will be readily apparent from a consideration of the foregoing. Briefly, when the pen 13 is not in the holder, the guide cup 18 is yieldingly supported in the uppermost portion 12 of the socket 11 by the light coil spring 22. This is shown to advantage in Figure 2 of the drawing. When the fountain pen is to be mounted in the holder, the pen point 19 and the nib 20 are engaged in the cup 18 with said point projecting through the opening 21. Thus, as the pen 13 is lowered into the holder against the tension of the coil spring 22, it is guided by the cup 18 and the elements 19 and 20 are prevented from touching any part of the holder other than said cup.

In the modification shown in Figure 5 of the drawing, the grooves or ways 14 are of a size and shape to accommodate a pair of coil springs 25 which are engaged beneath the end portions of the bar 17. In other respects, the construction and operation of this modification is substantially similar to the embodiment shown in Figure 1 of the drawing.

It is believed that the many advantages of a fountain pen holder constructed in accordance with the present invention will be readily understood, and although preferred embodiments of the device are as illustrated and described, it is to be understood that further modifications and changes in the details of construction may be resorted to which will fall within the scope of the invention as claimed.

Having described the invention, what is claimed as new is:

A pen holder comprising a body having a substantially cylindrical socket therein for the reception of the writing end portion of a pen, said socket having diametrically opposite, longitudinal grooves therein, a bar having its end portions slidably engaged in the sockets, a guide for the reception of the point of the pen mounted on said bar, coil springs in the grooves engaged beneath the bar for yieldingly urging the cup outwardly and means in the socket for releas-

5 ably securing the pen therein against the action of said coil springs.

BILLY N. VOELCKER.
